Primary Examiner — Shannon W Morgan*Assistant Examiner* — Altaira J Swangin(74) *Attorney, Agent, or Firm* — Dascentro Intellectual Property Law, P.C.; David S. D'Ascenzo(57) **CLAIM**

The ornamental design for a furniture handle, as shown and described.

DESCRIPTION

FIG. 1 is an isometric view of a furniture handle showing the design.

FIG. 2 is an end elevation view of the design of FIG. 1, the opposite end being a mirror image thereto.

FIG. 3 is a side elevation view of the design of FIG. 1, the opposite side being a mirror image thereto; and,

FIG. 4 is a top plan view of the design of FIG. 1.

The portions of the bottom of the furniture handle, not seen in the drawings, form no part of the claimed design.

1 Claim, 4 Drawing Sheets(56)
